UNITED STATES PATENT OFFICE.

ANDROV CARLSON AND FRANK A. SWANSON, OF CHICAGO, ILLINOIS.

TORPEDO-GUARD FOR SHIPS.

1,218,371.

Specification of Letters Patent.

Patented Mar. 6, 1917.

Application filed November 11, 1915. Serial No. 60,920.

To all whom it may concern:

Be it known that we, ANDROV CARLSON and FRANK A. SWANSON, citizens of the United States, and residents of the city of Chicago, county of Cook, and State of Illinois, have jointly invented certain new and useful Improvements in Torpedo-Guards for Ships, of which the following is a specification.

Our invention relates to improvements in 10 torpedo guards for ships, and has for its object the provision of improved means for preventing the torpedoing of a ship.

The invention consists in the combinations and arrangements of parts hereinafter described and claimed.

The invention will be best understood by reference to the accompanying drawings forming a part of this specification, and in which—

20 Figure 1 is a top plan view of a ship equipped with guarding means embodying our invention,

Fig. 2, a side elevation of the same,

Fig. 3, an enlarged detail elevation of one 25 complete guard section and the adjoining ends of two other guard sections,

Fig. 4, an enlarged transverse section taken through one side of the ship,

Fig. 5, an enlarged inside elevation of the 30 connection between two of the guard sections, and

Fig. 6, an enlarged detail section taken on line 6—6 of Fig. 4, illustrating the frictional mounting of operating gears for the guard.

35 The preferred form of construction, as illustrated in the drawings, comprises a torpedo guard arranged at each side of a ship of any usual or desired construction; said guard at each side consisting of alternating 40 hollow sheet metal buoyant sections 7 and 8, each of said sections being shaped on its inner side 9 to fit the curvature of the corresponding side 10 of the ship. Each of the sections 7 is embraced by two suspending 45 straps 11 attached at their upper ends to corresponding hangers 12 arranged to fit loosely over the squared ends 13 of operating rods 14 operating through stuffing boxes 15 arranged in the sides of the ship. Each of 50 the rods 14 is provided with a depending brace 16 secured to hanger 12 by bolts 17 and the end 13 is additionally secured to hanger 12 by means of a bolt 18 thus effecting a 55 strong, secure and readily detachable connection between each of the sections 7 and the corresponding pair of operating rods 14.

The adjoining ends of guard sections 7 and 8 are provided with internesting perforated ears or lugs 19 and bolts 20 are passed through said ears, thus effecting detachable 60 connections between the different guard sections permitting of their ready removal and replacement in case of damage.

The inner end 21 of each of the rods 14 is squared and mounted to run upon a guide 65 roller 21'. Each of the squared ends 21 carries on its upper side a rack bar 22 meshing with a gear 23 frictionally mounted on a sleeve 24 keyed to an operating shaft 25 extending along the corresponding side of the 70 ship. Each of the sleeves 24 is provided with a friction flange 26 contacting with one side of the corresponding gear 23 and a friction disk 27 loosely mounted on said sleeve contacts with the other side of the corresponding gear 23. A nut 28 is threaded on sleeve 24 adjacent the outer side of disk 27 by means of which the frictional mounting of the corresponding gear 23 may be adjusted. Each of the shafts 25 carries a worm 80 wheel 29 meshing with a worm 30 on the motor shaft of an ordinary electric motor 31 and by means of which each of the shafts 25 may be operated independently of the other, as will be readily understood.

In use the guard sections 7 and 8 are adjusted to rest closely against the sides of the ship, thus offering as little resistance as possible to the passage of the ship through the water, the guard sections 7 at each end 90 of the ship being provided with beveled or pointed ends for this purpose. When danger threatens from a torpedo fired by a submarine or otherwise, the guards 7—8 may be quickly extended from the sides of the ship 95 and will serve to intercept the torpedo and explode the same at a safe distance from the ship, the guard sections being arranged and positioned in the water to extend below the surface thereof to a suitable depth for the 100 purpose. In case of injury to any one of the sections, the same may be readily removed and replaced owing to the readily, detachable connections thereof. The guard sections 7—8 being air tight and buoyant, also 105 serve as air tight compartments tending to prevent sinking of the ship. In case a guard section received a severe blow or impact as in a collision or otherwise, the frictional connection between gears 23 and the corresponding shaft 25 permits of sufficient yielding of the guard sections to prevent or mini-

imize damage thereto from such a cause, but said frictional connection may be readily adjusted so as to afford sufficient resistance for adjusting the guard sections and effecting 5 explosion of a torpedo. By driving the shafts 25 by means of a worm meshing with a worm wheel thereon, said shafts are automatically locked against reverse motion due to impacts on the guard sections from waves, 10 torpedoes or otherwise.

While we have illustrated and described the preferred form of construction for carrying our invention into effect, this is capable of variation and modification without 15 departing from the spirit of the invention. We, therefore, do not wish to be limited to the precise details of construction set forth, but desire to avail ourselves of such variations and modifications as come within the 20 scope of the appended claims.

Having described our invention what we claim as new and desire to secure by Letters Patent is:

1. The combination with a ship, of a plurality of supports extending outwardly from the sides thereof; guard sections at the outer ends of said supports; and additional guard sections arranged between said first mentioned guard sections and detachably 25 connected therewith, substantially as described.

2. The combination with a ship, of a plurality of supports extending outwardly from the sides thereof; a hollow buoyant

sheet metal guard section arranged at the 35 outer end of each of said supports; additional guard sections arranged between said first mentioned guard sections and detachably connected therewith; and means for withdrawing or projecting said supports, 40 substantially as described.

3. The combination with a ship, of a plurality of hollow buoyant sheet metal guard sections therefor arranged at each side thereof and extending below the water a 45 suitable distance to intercept an approaching torpedo; straps embracing every other one of said guard sections; hangers connected with said straps; rods detachably connected with said hangers and sliding 50 through the side walls of the ship; detachable connections between the adjoining ends of the guard sections at each side of the ship; rack bars carried by said rods within the ship; an operating shaft arranged in operative relation with the rack bars at each side of the ship; gears frictionally mounted 55 on said shafts and meshing with said rack bars; and a worm drive for each of said shafts, substantially as described. 60

In testimony whereof we have signed our names to this specification in the presence of two subscribing witnesses.

ANDROV CARLSON.
FRANK A. SWANSON.
